(57) **CLAIM**

The ornamental design for a switch plate, as shown and described.

DESCRIPTION

FIG. 1 is a perspective view of a first embodiment of a switch plate according to the present invention.

FIG. 2 is a front view of the switch plate of FIG. 1.

FIG. 3 is a top view of the switch plate of FIG. 1. The bottom view is identical to the top view.

FIG. 4 is a first side view of the switch plate of FIG. 1. The opposite side view is identical.

FIG. 5 is a perspective view of a second embodiment of a switch plate according to the present invention.

FIG. 6 is a front view of the switch plate of FIG. 5.

FIG. 7 is a top view of the switch plate of FIG. 5. The bottom view is identical to the top view.

FIG. 8 is a first side view of the switch plate of FIG. 5. The opposite side view is identical.

FIG. 9 is a perspective view of a third embodiment of a switch plate according to the present invention.

FIG. 10 is a front view of the switch plate of FIG. 9.

FIG. 11 is a top view of the switch plate of FIG. 9. The bottom view is identical to the top view; and,

FIG. 12 is a first side view of the switch plate of FIG. 9. The opposite side view is identical.

The broken lines in the drawings do not form part of the claimed design.

1 Claim, 6 Drawing Sheets
